BRACKETING DEVICE

Albert C. Fischer and Robert D. Moyers,
Chicago, Ill.

Application January 18, 1937, Serial No. 121,038

10 Claims. (Cl. 72—101)

Our invention relates to an improvement in a bracketing device, the brackets being mounted singly or in series. The purpose of the bracket is to hold elements in alignment with a definite channel or course.

Our invention pertains to a sheet metal surface having a keyway therein and inserting in said keyway a bracket having a base portion which fits into the keyway and is locked into position by pressure of flanges on the base. The bracket arms extend outwardly from this base and outwardly from the keyway.

In the construction field particular facing plates are often used to maintain various construction materials in position. At times it is desirable to place dowels through these materials and facing plates, and unless the ends of the dowels are held in position there is danger when placing other materials about these facing plates that these dowels may become displaced, and it is for this purpose that these brackets, which otherwise might be stamped out of the facing plates, are made as separate and individual units and pressed into position wherever they may be desirable, thus making it convenient to shape the facing plates flatwise and the brackets separately. The brackets can be fitted into place on the job. While these brackets and facing plates may operate most effectively in the construction field we do not wish to be limited to this field.

Referring to the drawing:

Figure 1 is a perspective view of the present invention,

Figure 2 is a vertical sectional view along line 2—2 of Figure 1,

Figure 3 is a front elevation of the bracket,

Figure 4 is a horizontal sectional view of an assembly embodying opposed brackets, and,

Figure 5 is a vertical sectional view corresponding to Figure 2 of a different embodiment of the invention.

Figure 1 shows a type of construction material 10 having a facing plate 11 on either side. This facing plate 11 has a keyway 12 stamped therein, the shape of the keyway being apparent from the cross-sectional view. The bracket portion 13 fits into the depressed keyed edges 14 and is firmly held in position by the flanges 15. These flanges are shaped the same as the keyway edges 14 and with just sufficient spring to make it necessary to use force to press the base 13 of the bracket into position between the keyway ridges 14. From the base 13 of the bracket extend

This product may be utilized as a supporting bracket, so to speak, by imbedding the arms 16 into a cementitious block or substance and using the base 13 of the bracket as a supporting means, or the base of the bracket may be the seat of the bracket and the arms used for suspending various materials thereon, or modifications may be made in these arms for various purposes.

Figure 2 shows a sectional view of the bracket in which the base 13 is pressed into the facing 10 keyway 12. This view also shows the locking ridges 14 and the base portion 13, together with the flanges 15 pressed therein. The extension represents the arm or arms of the bracket.

Figure 3 shows the bracket in detail, in which 15 13 represents the base of the bracket, 15 the outwardly projecting flanges for interlocking in the keyway ridges 14, and the projecting arms 16 each having a turned flange 17, which turned flange has an opening 18 therein to receive dowel 20 supports and an opening 19 for the receiving of a rivet or other fastening means in drawing oppositely aligned brackets together. It will be noted that the arms 16 project from the base section 13 directly from the edges 20 and independent from flanges 15, which project outwardly and are the locking means of the bracket between the rigid keyways 14. When the bracket in Figure 3 is pressed into position, as in Figure 1, the shape of the base of the bracket will hold 25 it firmly in position without the possibility of sagging the bracket by pressing on either arm. It can further be held in position by a rivet through the opening 19 in Figure 3 extending through opposite keyways and opposite brackets 35 so that the two bases of the respective brackets can be drawn up together with the facings into one comprehensive whole. Openings 22 in the foundation plate 10 are shown in Figure 4, the openings 18 being adapted to receive dowel bars 40 21 which penetrate through the material and the apertures 18 thereby to hold the dowel bar firmly in position without danger of tilting.

It can readily be understood that the bracket may operate from the extension arms and support a facing plate with a keyway, or the ends of the arms may support a device extending through the facing plate and lateral extensions of the arms. This device may extend through to an opposite bracket on the other side, thus 50 holding this bar or device in a fixed position while other materials may be placed about it, depending upon the purpose for which the bracket and facing plate are to be used.

Likewise, these brackets may be mounted in 55

series along a facing plate in a continuous keyway, or they may be oppositely mounted or staggered, depending upon the purpose for which they are to be used. Likewise, they can be employed without any bar or rod arrangement and used merely for the purpose of holding one surface against another surface, or in spaced relation from that other surface, or it may be desirable to use these brackets in connection with bars, which would slip through the openings at 18, penetrate the opposite face and be anchored at the end of the extension arms in an opposing face as shown in Figure 4. In highway construction undoubtedly these facing plates would be utilized 15 in numerous ways for the support of dowel bars.

The keyway likewise need not necessarily be depressed but a ridge may be outwardly crimped so that it would not be necessary to indent the material housed between the facing plates. Such 20 a construction is shown in Fig. 5 wherein 30 indicates ridges in the foundation support 10 on which are crimped the flanges 35 on the base 33 from which extend the arms 36.

Likewise the bracket may be inserted in a 25 concrete facing or any kind of monolithic facing, or the keyway may be impressed into any sort of surface and the bracket locked therein in some manner, in which case the facing plate with the keyway would be eliminated and the 30 keyway impressed either into the monolithic structure or into any structural material which may be solid enough to hold the bracket.

This bracket and keyway facing may be made 35 of metal, wood, any composition or other material, and likewise, the building element may be composed of any type of material which may be acceptable for its use. The bracket may be prepared from sheet metal or any of the metals, whether sheet, cast or wrought, or out of any 40 other composition as long as they can be shaped and accomplish the locking feature with the keyway intended.

The disclosures of this application are 45 illustrative and the invention is not to be limited by them. In fact, if modifications or improvements are not at once obvious, they may be devised in the course of time to make additional use of the broad ideas taught and covered by this application. The claims are intended to 50 point out novel features and not to limit the invention except as may be required by prior art.

We claim:

1. In combination, a foundation support having a keyway formed therein, a bracket having 55 a base of substantial surface area and resilient flanges extending therefrom, said base adapted to be set in said keyway adjacent said foundation support by means of said resilient flanges engaging therein, and arms extending from said base at portions thereof other than said flanges.

60 2. In combination, a metallic facing plate having a keyway formed therein, a bracket having a base of substantial surface area, means for fixing said bracket within said keyway at said base to retain said bracket adjacent to said facing plate, and arms extending from said base independently of said fixing means.

65 3. A structural assembly comprising a facing plate formed with a keyway therein, a bracket adapted to be retained in said keyway having a 70

base of substantial surface area adapted to be disposed in said keyway, flanged portions extending from said base adapted to be engaged in said keyway to dispose said base adjacent to said facing plate, and arms extending from said base.

4. A structural assembly comprising a facing plate provided with a keyway, a bracket adapted to be fixed in said keyway having a base of substantial surface area and resilient flanges extending therefrom adapted to be interlocked in said keyway, and arms extending from opposite sides of said base between said resilient flanges adapted for attachment to structural elements. 10

5. In combination, a metallic facing plate having a keyway formed therein, a bracket having a base of substantial surface area, resilient flanges for fixing said bracket within said keyway at said base, and arms extending from said base independently of said fixing means. 15

6. In combination, a metallic facing plate having a keyway formed therein, a bracket having a base, resilient flanges for fixing said bracket within said keyway at said base, supplemental means for attaching said bracket to said facing plate, and arms extending from opposite sides of said base between said resilient flanges adapted to support structural elements. 20

7. A structural assembly comprising a foundation support, a guiding element formed on each side of said support in opposing relationship, brackets adapted to be attached to said guiding elements, each of said brackets having a base provided with means for attachment thereof to said guiding elements, arms extending transversely from said base, and lateral extensions on said arms substantially parallel to the base of its bracket provided with apertures adapted to receive dowel bars extending through said foundation. 30

8. A building unit provided with a guiding element, a bracket detachably connected to said guiding element having a base of substantial surface area adjacent said guiding element and flanges integral with said base in interfitting engagement with said guiding element, and arms projecting outwardly from said base for attachment to structural elements. 40

9. A foundation support provided with a ridge on at least one face thereof, a plurality of brackets attached to said ridge, each of said brackets comprising a base of substantial surface area adjacent to said ridge and arms extending outwardly from said base, and means for clamping said base to said ridge. 50

10. A structural assembly comprising a foundation support, a guiding element formed in each side of said support in opposing relationship, brackets adapted to be attached to said guiding elements in opposed alignment, each of said brackets having a base adjacent to said guiding elements and arms extending outwardly therefrom, flanges attached to said bases for attachment to said guiding elements, and supplemental means extending through pairs of opposed brackets for the attachment thereof to said foundation support. 60
